UNITED STATES PATENT OFFICE.

FRANK J. MONZ, OF NEW HAVEN, CONNECTICUT, ASSIGNOR TO THE
SARGENT & COMPANY, OF SAME PLACE.

DOOR-KNOB.

SPECIFICATION forming part of Letters Patent No. 651,552, dated June 12, 1900.

Application filed March 5, 1900. Serial No. 7,399. (No model.)

To all whom it may concern:

Be it known that I, FRANK J. MONZ, a citizen of the United States, residing in New Haven, in the county of New Haven and State of Connecticut, have invented certain new and useful Improvements in Door-Knobs, whereof the following is a full, clear, and exact description when taken in connection with the accompanying drawings, which form a part thereof.

My invention relates to the construction and arrangement of the knob-shank and of the knob-shell, whereby the same may be conveniently fastened together without the intervention of a separate fastening device.

In the accompanying drawings, Figure 1 is a plan view of the inner half of the knob-shell secured to the knob-shank, the outer portion of the knob-shell being omitted. Fig. 2 is a cross-section of the same through the line $\alpha\alpha$. Fig. 3 is a section of the same parts before the two are united.

In all figures similar letters of reference represent like parts.

The knob-shank is constructed, as shown in Fig. 3, with a shoulder at a near one end and a circular neck b projecting therefrom. Otherwise the knob-shank is of the ordinary construction.

The knob-shell, which may be of sheet metal, is constructed at its corresponding

parts with a sleeve fitting over the neck b and an annular flange at right angles thereto fitting down upon the shoulder a . The neck b projects slightly beyond the sleeve on the 35 knob-shell. This portion of the neck b , which extends above the sleeve of the knob-shell, is now pressed outward and downward over the end of the sleeve, so as to hold the bearing-surfaces firmly together. This operation 40 may be performed by swaging, and it results in a very firm and secure union of the knob shank and shell without the intervention of any independent fastening device.

Having now described my invention, what 45 I claim, and desire to secure by Letters Patent, is—

In combination with the shank A, having the shoulder a and neck b at right angles to each other, of a knob-shell B, having a corresponding flange and sleeve adapted to fit over and upon said surfaces a and b ; the end of the neck b being bent outward and downward over the end of the sleeve on the knob-shell, so as to hold the said bearing-surfaces 55 together, substantially as described.

In witness whereof I have hereunto set my hand this 28th day of February, 1900.

FRANK J. MONZ.
